SPECIFICATION forming part of Design No. 33,058, dated August 14, 1900.

Application filed July 13, 1900. Serial No. 23,537. Term of patent 7 years.

To all whom it may concern:

Be it known that I, NICHOLAS WITSCH, a citizen of the United States, residing at No. 100 Palisade avenue, Jersey City, in the county of 5 Hudson and State of New Jersey, have invented and produced a new and original Design for a Label, of which the following is a specification, reference being had to the accompanying drawings, forming a part thereof.

- o My design is intended for use as a label.

In the accompanying drawing the design is shown on a rectangular panel.

The design comprises in a rectangular panel the representation of a table upon which 5 stands an inkstand with the cap open and a quill inserted therein; also, a lighted cigar which extends over the edge of the table. In the background is the representation of a

curtain-draped back. The central portion of the design is occupied by a scroll, apparently ready to be written upon, the lower right-hand corner of which shows a seal, with a pair of balances in the center. The remainder of the design consists of an ornamental border and leaf-and-scroll work. 20 25

I claim—

The design for a label as herein shown and described.

In testimony whereof I, NICHOLAS WITSCH, affix my signature in presence of two witnesses. 30
